Nelson M. Wood

UNITED STATES PATENT OFFICE.

CHESTER HUNT, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR APPLYING ADHESIVE STRIPS TO SOLES.

Application filed March 18, 1922. Serial No. 544,952.

This invention relates to machines for applying adhesive strips to soles and is herein illustrated as embodied in a machine for applying to the edge and an adjoining face of

5 a semi-vulcanized rubber sole a strip of unvulcanized rubber.

In the manufacture of certain rubber-soled shoes, and more particularly in the manufacture of sporting shoes such as those used in playing basket ball, it is customary to prepare a semi-vulcanized rubber sole and to incorporate the sole in a shoe having a canvas upper. Such a shoe is subjected to great strain in use, and for this reason must be made particularly strong. Vulcanization will not form a sufficiently strong bond between the canvas upper and the semi-vulcanized sole; and it is, therefore, customary to apply a thin strip of unvulcanized rubber around the margin of the upper face of the sole before the sole is applied to the bottom of the lasted shoe so that the subsequent vulcanizing operation may effect the desired bonding. Commonly one portion of a strip 20 of unvulcanized rubber is applied, as described above, to the margin of the upper face of the sole, and another portion is bent down and applied to the edge of the sole. After the sole has been applied to the lasted shoe, but before the vulcanization has taken place, a foxing of unvulcanized rubber is applied around the lower margin of the sides of the shoe adhering in part to that portion 25 of the strip which covers the edge of the sole and in part to the canvas upper; and by reason of the presence of this foxing the vulcanization of the shoe results in a further bonding of the upper to the sole.

The general object of the present invention is to provide a machine for applying to a sole or similar article a strip of the type referred to above. In the illustrative machine a strip guide, shaped to bend the strip approximately at right angles along a line 30 running lengthwise of the strip, directs the bent strip to the edge and one face of a sole, the sole and strip being fed and the bent strip pressed into place by a series of rollers including two presser rollers and a feed roller.

50 This and other features of the invention including certain details of construction and combinations of parts will be described as

embodied in an illustrative machine and pointed out in the appended claims.

Referring now to the accompanying drawings,

Figure 1 is a perspective of a machine in which the present invention is embodied;

Figure 2 is a front elevation;

Figure 3 is an end elevation, and

Figure 4 is a perspective of a semi-vulcanized rubber sole to which a strip of unvulcanized rubber has been applied by the machine.

The illustrative machine comprises three 65 rollers, a feed roller 5, an edge pressing roller 7, and a face pressing roller 9. The sole is forced against the roller 9 and fed along by the feed roller 5. This feed roller is loose on a vertical shaft 11 and may be formed of 70 fibre disks clamped between washers 13, 15. Mounted loosely on the shaft 11 above the feed wheel is a friction fibre disk 17, and similarly mounted below it is a friction fibre disk 19. The upper face of the upper disk 75 17 rests against the flat under face of a sleeve 21 which is fast to the shaft 11; and the under face of the lower disk 19 rests upon the upper face of a washer 23. A coiled compression spring 25 surrounds the lower portion of the shaft 11 with its upper end abutting against the disk 23 and its lower end resting upon an adjusting nut 27 threaded upon the lower end of the shaft. A lock nut 29 holds the nut 25 from accidental turning. The purpose 80 of the construction which has just been described is to provide a friction drive for the feed wheel.

The shaft 11 is mounted in a bracket 31 which is pivotally mounted about the axis of 90 a second vertical shaft 33 and has a tail 35 extending rearwardly from it which is connected by a tension spring 37 with one end of a pin 39, said pin being adjustably held in a bore in a stationary part of the machine by 95 a set screw 41. With this construction the feed roller 5 is held yieldingly against the sole at all times during the operation of the machine. When no work is in the machine the position of the feed roller is determined by a stop (not shown). The shaft 11 has fast to it a gear 43 which meshes with a gear 45 fast upon the lower end of the shaft 33, the upper end of said shaft carrying a gear 47

which meshes with a worm 49 on a horizontal driving shaft 51 which may be rotated by means of a pulley 53 from any suitable source of power.

The two rollers 7 and 9 are mounted in the following manner in a bracket, the two arms 55, 57 of which are fastened to the frame of the machine by bolts 59, 61. Projecting from the bracket is an elongated lug 63 having a slot through which passes the upper end of a spindle 65, the spindle being held in adjusted position in the slot by a butterfly nut 67, and the roller 9 being rotatably mounted on the lower end of the spindle. The roller 7 is rotatably mounted on a spindle 69 the outer end of which is flattened and has a socket to receive the lower end of a compression spring 71. The spindle at its inner end is pivoted at 73 to a downwardly extending portion of the roller-carrying bracket and has a tail which normally contacts with the under face of the bracket 31 and serves thereby to limit the extent to which the roller 7 may be swung by the spring 71. The purpose of so mounting the roller 7 is to cause it to press the rubber strip evenly against the edge of the sole whether or not the plane of that edge forms a right angle with the plane of the upper face of the sole.

Referring now more particularly to Figure 4, it will be seen that the unvulcanized rubber strip 200 has been bent along a line parallel to its length and that the portions on opposite sides of the bend have been applied respectively to the edge and to the upper face of the sole. In order to deliver the strip of unvulcanized rubber to the sole in such manner that it will be laid as shown in Figure 4, a strip-guide 75 is mounted on the lower end 40 of an arm 77 which is pivoted about the axis of the bolt 61. A tension spring 79, fast at its upper end to a fixed pin and at its lower end to a pin driven into the arm 77, normally holds the arm in its operative position and 45 against a stop pin 81. The arm 77, and with it the strip-guide 75, may be swung to the left (as viewed in Figure 3) when desired, the extent of its movement in this direction being limited by a second stop pin 83. The stop pins are so located with respect to the axis of the bolt 61 that the strip guide will be held by 50 the spring 79 in either of the two positions into which it may be swung by the operator. The strip guide is provided with a hinged 55 cover held down by a suitable clamping device fastened by a thumb-screw 85, the guide-way in the strip guide being shaped to cause a strip drawn through it to be bent substantially at right angles along a line parallel to 60 one edge of the strip and spaced farther from one edge than from the other. The main portion of the strip thus remains in its original substantially horizontal position while a comparatively narrow margin is bent downwardly, the line of bend being so located that the

main portion of the strip covers the whole edge of the sole, and the bent down margin is applied to the upper face of the sole.

In the operation of the machine a strip 200 is laid upon a table 87, as shown in Figure 1, 70 with its forward end projecting through the strip guide 75. The operator then presents a sole 100 in the position shown in full lines in Figure 1 and in dotted lines in Figure 2 and guides the sole as it is being fed until the strip 75 200 has been laid all around the edge of the sole.

Having thus described my invention, what I claim as new and desire to secure by Letters Patent of the United States is:—

1. A machine of the class described having, in combination, means for feeding a sole, means for guiding to the sole in adhesive unattached strip so bent that it extends over the edge and the adjacent portion of the top 85 face of the sole, and means for pressing the strip into firm contact with said edge and face.

2. A machine of the class described having, in combination, means engaging the top and 90 bottom face of a flexible sole to feed it, a strip guide constructed and arranged to bend a strip prior to its contact with the sole and deliver the strip to the edge and top face of the sole, and means, including the feeding means, 95 for pressing the strip firmly into place.

3. A machine for applying an adhesive strip over the corner at the junction of the edge and one face of a sole having, in combination, three rollers arranged to engage the 100 edge and the adjacent margins of the opposite faces of a sole, means for driving one of the margin-engaging rollers to feed the sole, and a guide constructed and arranged to bend a strip and deliver it to the edge and one 105 face of the sole in position to be engaged by two of the rollers.

4. A machine for applying an adhesive strip over the corner at the junction of the edge and one face of a sole having, in combination, three rollers arranged to engage the 110 edge and the adjacent margins of the opposite faces of a sole, yielding means for driving one of the margin-engaging rollers to feed the sole, and a guide constructed and arranged to bend a strip and deliver it to the edge and one 115 face of the sole in position to be engaged by two of the rollers.

5. A machine for applying an adhesive strip over the corner at the junction of the 120 edge and one face of a sole having, in combination, three rollers arranged to engage the edge and the adjacent margins of the opposite faces of a sole, means for driving one of the margin-engaging rollers to feed the sole, a 125 guide constructed and arranged to bend a strip and deliver it to the edge and one face of the sole in position to be engaged by two of the rollers, a pivot upon which the guide is mounted, and a spring for holding the 130

guide normally in operative position while permitting it to be swung out of operative position when desired.

6. A machine for applying a strip of unvulcanized rubber over the corner at the junction of the edge and one face of a rubber sole having, in combination, a strip guide comprising a member having a guideway shaped to bend a strip drawn through it along a line parallel to an edge of the strip so that the portions of the strip on opposite sides of the bend will be adapted to contact respectively with the edge and a face of a sole presented to the bent strip, a roller located to press one portion of the strip against the edge of the sole, a second roller for pressing the other portion of the strip against the face of the sole, and a feed member adapted to press the sole against the second roller.
- 10 7. A machine for applying a strip of unvulcanized rubber over the corner at the junction of the edge and one face of a rubber sole having, in combination, a strip guide comprising a member having a guideway shaped to bend a strip drawn through it along a line parallel to an edge of the strip so that the portions of the strip on opposite sides of the bend will be adapted to contact respectively with the edge and a face of a sole presented to the bent strip, a roller located to press one portion of the strip against the edge of the sole, a pivot about which said roller may swing, a spring for urging the roller toward the sole, a second roller for pressing the other portion of the strip against the face of the sole, and a feed member adapted to press the sole against the second roller.
- 15 8. A machine for applying a strip of unvulcanized rubber over the corner at the junction of the edge and one face of a rubber sole having, in combination, a strip guide comprising a member having a guideway shaped to bend a strip drawn through it along a line parallel to an edge of the strip so that the portions of the strip on opposite sides of the bend will be adapted to contact respectively with the edge and a face of a sole presented to the bent strip, a roller located to press one portion of the strip against the edge of the sole, a pivot about which said roller may swing, a spring for urging the roller toward the sole, a second roller for pressing the other portion of the strip against the face of the sole, and a feed member adapted to press the sole against the second roller.
- 20 9. A machine for applying a strip of unvulcanized rubber over the corner at the junction of the edge and one face of a rubber sole having, in combination, a strip guide shaped to bend a strip passing through it in such manner that a portion of the strip will be applied to the edge of the sole and a second portion to the face of the sole, a roller arranged to press said second portion against the face of the sole, a driven yieldingly-mounted feed roller arranged to engage the opposite face of the sole, and a yieldingly mounted roller for pressing the first-named portion against the edge of the sole.
- 25 10. A machine for applying a strip of unvulcanized rubber over the corner at the junction of the edge and one face of a rubber sole having, in combination, a strip guide shaped to bend a strip passing through it in such manner that a portion of the strip will be applied to the edge of the sole and a second portion to the face of the sole, a roller arranged to press said second portion against the face of the sole, a driven yieldingly mounted feed roller arranged to engage the opposite face of the sole, an edge presser arranged to press the first-named portion of the strip against the edge of the sole, a pivot about which the presser may swing, and a spring for urging the presser about the pivot.
- 30 11. A machine for applying a strip of unvulcanized rubber over the corner at the junction of the edge and one face of a rubber sole having, in combination, a strip guide shaped to bend a strip passing through it in such manner that a portion of the strip will be applied to the edge of the sole and a second portion to the face of the sole, a roller arranged to press said second portion against the face of the sole, a driven, yieldingly mounted feed roller arranged to engage the opposite face of the sole, an edge roller arranged to press the first-named portion of the strip against the edge of the sole, a pivot about which the edge roller may swing, and a spring for urging the roller about the pivot.
- 35 50

portion of the strip against the face of the sole, and a rotary feed member adapted to press the sole against the second roller. 55

9. A machine for applying a strip of unvulcanized rubber over the corner at the junction of the edge and one face of a rubber sole having, in combination, a strip guide shaped to bend a strip passing through it in such 60 manner that a portion of the strip will be applied to the edge of the sole and a second portion to the face of the sole, a roller arranged to press said second portion against the face of the sole, a driven yieldingly-mounted feed roller arranged to engage the opposite face of the sole, and a yieldingly mounted roller for pressing the first-named portion against the edge of the sole.

10. A machine for applying a strip of unvulcanized rubber over the corner at the junction of the edge and one face of a rubber sole having, in combination, a strip guide shaped to bend a strip passing through it in such manner that a portion of the strip will be applied to the edge of the sole and a second portion to the face of the sole, a roller arranged to press said second portion against the face of the sole, a driven yieldingly mounted feed roller arranged to engage the opposite face of the sole, an edge presser arranged to press the first-named portion of the strip against the edge of the sole, a pivot about which the presser may swing, and a spring for urging the presser about the pivot. 80

11. A machine for applying a strip of unvulcanized rubber over the corner at the junction of the edge and one face of a rubber sole having, in combination, a strip guide shaped to bend a strip passing through it in such 90 manner that a portion of the strip will be applied to the edge of the sole and a second portion to the face of the sole, a roller arranged to press said second portion against the face of the sole, a driven, yieldingly mounted feed roller arranged to engage the opposite face of the sole, an edge roller arranged to press the first-named portion of the strip against the edge of the sole, a pivot about which the edge roller may swing, and a 95 spring for urging the roller about the pivot.

In testimony whereof I have signed my name to this specification.

CHESTER HUNT.
